UNITED STATES PATENT OFFICE.

BERTIE THOMAS OLIVER, OF WALLINGTON, WILLIAM THOMAS BURBEY, OF LONDON,
AND THOMAS GRIMES, OF WESTCLIFF-ON-SEA, ENGLAND.

TOY GUN.

1,185,431.

Specification of Letters Patent. Patented May 30, 1916.

Application filed August 12, 1915. Serial No. 45,109.

To all whom it may concern:

Be it known that we, BERTIE THOMAS OLIVER, manufacturer, of "Gulval," Grosvenor Road, Wallington, Surrey, England, 5 WILLIAM THOMAS BURBEY, manufacturer, of 161 Boundaries Road, Balham, London, S. W., England, and THOMAS GRIMES, manufacturer, of "Glentana, Sandown avenue, Westcliff-on-Sea, England, subjects of the 10 King of Great Britain, have invented new and useful Improvements in Toy Guns; and we do hereby declare the following to be a full, clear, and exact description of the invention, such as will enable others skilled in 15 the art to which it appertains to make and use the same.

This invention relates to toy guns wherein spring means are employed as the propelling force, and has for its object the provision of new or improved means of the 20 above type which shall be simple and powerful in action and easy to construct and which shall impart to the gun a more realistic appearance than heretofore.

25 The invention consists broadly in a radially working propelling arm arranged to move in a path approximately coincident with the central longitudinal axis of the gun with means, in conjunction therewith for re- 30 tracting such arm to the rear of the gun against the action of a suitable spring or springs and further means, releasable by the pressure of the finger, for retaining the same in such position of tension.

35 One practical application of the invention is illustrated by the accompanying drawings in which:—

Figure 1 is a side elevation of the complete gun with the breech cap or cover 40 partly open. Fig. 2 a central vertical section of the gun illustrated in Fig. 1. Fig. 3 an underside plan view with the carriage removed to more clearly show the mechanism. Fig. 4 a top plan view of Fig. 1 with 45 the breech cap or cover in the open position.

In the drawings, 10 represents the gun carriage as a whole consisting of two portions 11 and 12 each stamped in one piece from sheet metal and connected together by

lap joints as at 13 and 14. The forward end 50 of each portion 11 and 12 is formed with an upstanding triangularly shaped piece 15 having each at their upper points an alined aperture within which the gun is pivotally mounted by means of trunnions 16. An arcuate slot 17 is cut in the side of one of the pieces 15 having as its center the corresponding alined aperture for a purpose hereafter to be described. The gun portion, as distinct from the carriage 10 and will hereafter be referred to by the numeral 18, comprises a barrel 19 formed from a length of metal tubing having at its rear or breech end a portion removed by cutting along a horizontal axis so as to divide the tube at 60 65 that portion into two halves the upper of which is then completely removed by cutting across at right angles to the other cut at the termination thereof thus exposing the interior and forming a semi-circular receptacle 70 75 20 into which the ammunition is placed previous to being expelled. A further cut away portion or slot 21 is formed in this receptacle 20 extending inwardly for a convenient distance from the rear thereof thus leaving two side pieces 22 which are then bent at right angles so as to oppose each other at their extremities as at 23 leaving a narrow space through which enters the striking or expelling arm 24 to within the slot 21.

80 The breech end of the barrel 19 is partly enveloped by a metal covering 25 having an opening in its top arranged so as to coincide with the recess 20 in the gun barrel which coincident opening is provided with a hinged 85 cover 26 of an external contour conforming to the top surface of the covering 25 so that when such cover is in the lowered or closed position a continuous surface is presented. The forward end of this covering 25 has two 90 ears 27 which depend from each side of the barrel 19 and are secured beneath it by a binding screw 28 so as thereby to clamp the barrel and covering tightly together.

95 Centrally beneath the pivotal axis of the gun 18 as exemplified by the trunnions 16 the covering 25 depends, on one side only, downwardly and outwardly as at 29 so that

the extremity of the same is brought close up to the arcuate slot 17 and is there engaged by a clamping screw 30, the collar 30^a of which is without the slot 17. By these 5 means the gun 18 may be retained at any desired elevation.

The rear of the covering 25 is cut to the form of a strip 31 which in width is approximately equal to or slightly greater than the 10 barrel 19 and is bent so as to depend vertically downward for a portion of its length as at 31^a the remaining portion sloping slightly outwardly so as to lie at a convenient angle to the vertical. Riveted at its 15 upper end to the portion 31^a is a blade spring 32 depending vertically downward for a convenient distance and having a detent 33 struck from its body at or about its center. This detent is adapted to engage the 20 head of the striking arm 24, see Fig. 1, when the same is in the lowered or firing position.

The striking arm 24 is for preference, stamped from a sheet of metal and is formed at its upper forward edge with a 25 rounded portion 34 adapted to contact with the missile when expelling the same from the gun so as to obtain a hit as clean and sharp as possible. This arm 24 is supported upon a pivot pin 35 between the depending 30 sides of the covering 25, a suitable bearing being provided in the form of a length of tubing 36 which fits exactly between the said depending sides thus correctly positioning the striking arm 24 to 35 which it is secured. The arm is thus capable of a radial movement about the pin 35. To resist this movement in a backward direction and also to provide the necessary impetus for firing when the arm is released 40 from the detent 33 a spring 37 is coiled around the exterior of the tube 36 with one extremity resting against the exposed under part of the trunnion pin 16 and the outer extremity engaging a notch 38 cut out of 45 the edge of the arm 24, the whole being always in tension, that is tending to force the said arm into the vertical position assumed after firing and shown in Figs. 1 and 2. The notch 38 is in the example cut 50 at the point in the arm 24 where the same is bent to enable the upper or striking portion to lie coincident with the central longitudinal axis of the gun.

Extending from the lower portion of the 55 arm 24 beneath the pin 35 is a foot 39 the extremity of which is bent so as to protrude beyond the cover 25. This foot is engaged by a radially arranged catch piece 40 formed at the lower end of a lever 41 which lever 60 is loosely mounted upon one extremity of the pin 35 and is provided at its upper end with a handle 42 so that the same may be moved radially about its pivot. This movement, in a backward direction, is resisted by

a coiled spring 43 one extremity of which 65 is secured to the said pin 35 while the other engages a lip 44 struck from the lever 41. A bridge piece 45 is provided, adapted to rest upon the upper surface of the trunnion pin 16 and having upwardly extending 70 wings 46 the rear one of which projects into the path of the arm 24 so as to take the force of the blow when firing and thus prevent damage to the barrel 19.

In operation the clamping screw 30 is released and the gun 18 turned about its trunnions 16 until the desired elevation is attained, after which the screw is again tightened. The lever 41 is then pulled over by means of the handle 42 taking with it 80 the striking arm by reason of the engagement between the two by means of the foot 39 and radial catch piece 40. This backward movement is continued until the arm 24 has passed under the detent 33. The 85 lever 41 is then released, the spring 43 returning the same to its normal position as indicated in Fig. 1, leaving the striking arm 24 in engagement by the said detent 33. The cap or cover 26 is now raised exposing 90 the interior of the chamber 20 into which is placed the missile to be fired. This may be of wood and circular in shape with a pointed nose and square back end or any other convenient shape of device may be used. When 95 the missile is in position with its back end hard against the inturned extremities 23 the cover 26 is closed and the spring 32 retracted toward the portion 31 thus releasing the arm 24 from engagement by the detent 100 33 which immediately flies to the vertical position under the influence of the spring 37 and strikes the missile reposing in the recess 20 expelling the same with considerable force through the barrel 19.

What we do claim as our invention, and desire to secure by Letters Patent, is:—

1. In a toy gun, the combination of a mount, a breech casing pivoted to the mount, a barrel fixedly secured to the breech casing, a spring actuated firing hammer pivoted in the breech casing and having a lateral extension on its inner end, a cocking lever pivoted on the breech casing externally thereof and having its pivot in line 110 with the pivot of the firing hammer, means constantly tending to hold the cocking lever in forward position, a nib on the cocking lever engageable with the lateral extension on the hammer to retract the hammer when 115 said lever is moved rearwardly, and means for releasably holding the hammer in retracted position.

2. In a toy gun, the combination of a mount, a breech casing pivoted to the mount, 125 a barrel fixedly secured to the breech casing, a spring actuated firing hammer pivoted in the breech casing, means for retracting the

hammer, a spring arm depending from the rear end of the breech casing and having its upper end rigidly secured thereto, and a detent on the arm engageable with the hammer to releasably hold the latter in retracted position, said detent being disengaged from the hammer by flexing said spring arm rearwardly.

In testimony whereof we have signed our

names to the specification in the presence of 10
two subscribing witnesses.

BERTIE THOMAS OLIVER.
